Inventor

UNITED STATES PATENT OFFICE.

SAMUEL STEIN, OF ROCHESTER, NEW YORK.

DESIGN FOR BURIAL-CASE.

Specification forming part of Design No. 5,363, dated November 14, 1871.

To all whom it may concern:

Be it known that I, SAMUEL STEIN, of Rochester, in the county of Monroe and State of New York, have invented or produced a new and original Design for Burial-Cases, of which the following is a specification:

The nature of my design is fully represented in the accompanying drawing, to which reference is made.

A B C D represent a frame constructed of silver moldings, into which the two wooden pilasters E are framed. These pilasters are made with central ornamental tablets P, upon which the plates of the metal handles are secured. The handle plates each have raised buttony crosses upon their faces. At the bottom of the case ornamenteally-carved or slotted moldings x x are shown projecting above the base molding D. A heavy plate of glass, I, fills the entire panel constit-

tuting one side of the burial-case. The two pilasters E, with their tablets P, are outside of the glass plate I, but the ornamenteally-worked molding x x is placed against the inner surface of the glass panel I. The mountings V upon the molding A are placed in a vertical plane directly over the pilasters E to make the proper finish, as represented.

What I claim as my invention is—

A design for a burial-case, in which the moldings A B C D constitute a border for the sides, inclosing the glass panel I, ornamental wood work E x, and tablets P, substantially as above described.

In testimony whereof I have hereunto set my hand this 9th day of October, A. D. 1871.

Witnesses: SAMUEL STEIN.
